Burnham & Stickney

UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,237,258.

Specification of Letters Patent. Patented Aug. 14, 1917.

Application filed December 13, 1910. Serial No. 597,117.

To all whom it may concern:

Be it known that I, BURNHAM C. STICKNEY, a citizen of the United States, residing in Elizabeth, in the county of Union and 5 State of New Jersey, have invented certain new and useful Improvements in Combined Type-Writing and Computing Machines, of which the following is a specification.

This invention relates to calculating machines combined with writing mechanism, and more particularly to means for determining whether the calculating mechanism shall add or subtract, or remain neutral or ineffective at the operation of the writing 10 mechanism. It also relates to means for shifting the ribbon mechanism so that amounts to be subtracted may be written in a different color from other amounts.

I have provided that certain of the tabulating keys for the typewriter carriage shall be capable of shifting or reversing the action of the computing mechanism, so that, for instance, when the tabulating mechanism is operated to bring the typewriter carriage to 15 position for writing in the first column of numbers on the work sheet, the machine shall be set by such tabulating mechanism to add the number written; when the tabulating mechanism is operated to bring the carriage to the second column of writing on the work sheet, said tabulating mechanism shall reverse the operation of the computing mechanism so that the number written in the second column shall be subtracted; by suitable means the number written in the third 20 column may be added, while the number written in the fourth column may be neither added nor subtracted, and so on as may be desired; the tabulating mechanism having control of the computing devices to determine whether at any particular time they shall add or subtract or remain neutral.

I also preferably connect to the tabulating keys means for shifting the ribbon mechanism, so that the device shall print red or any other special color when writing in a column in which the numbers are being subtracted.

The present improvements are illustrated 50 in connection with column-skipping or column-selecting keys; but it will be under-

stood that the invention may be carried out in connection with other kinds of tabulating mechanism.

In the accompanying drawings, 55

Figure 1 is a sectional side elevation of the forward portion of the tabulating key levers, showing one of the keys depressed and as having effected a movement of the shifting mechanism to position for subtraction. 60

Fig. 2 is a similar view, showing another key as having moved the same to position for addition.

Fig. 3 is a sectional side elevation of an Underwood typewriting and computing machine with the present improvements applied thereto, and showing the computing mechanism in neutral position, so that no computation will be performed thereon when the numeral keys are operated. 65

Fig. 4 is a part sectional rear elevation of the typewriting, tabulating and computing mechanisms.

Fig. 5 is a sectional plan view of the same.

Fig. 6 is a diagram showing the ribbon 75 lever shifted to position for causing the device to strike through the red or special stripe of the ribbon.

Fig. 7 is a side elevation showing the connection between the tabulating key levers 80 and the ribbon shifting mechanism.

Figs. 8 and 9 are diagrams similar to Fig. 6, and showing that the ribbon shifting lever is in position for causing the black stripe of ribbon to become effective when the typewriting machine is writing in either the addition column or the neutral column. 85

Fig. 10 is a perspective view of a set of special stops employed for connecting the typewriter carriage intermittently with the computing mechanism, and also constructed to enable the tabulating keys to select the columns at which the carriage shall be arrested.

The invention is illustrated in connection with a machine in which the computing 95 wheels remain stationary while the master wheel moves step-by-step, being for that purpose connected to the paper carriage of the type writing machine. This connection is made at the beginning of the writing of each 100 column, and is automatically broken at the conclusion of the writing of each column.

The improvements may however be used in connection with other constructions of computing mechanism.

In the Underwood machine, numeral keys 1 depress levers 2 to vibrate bell cranks 3, and swing type bars 4 up to strike rearwardly against the front side of a platen 5. Said platen is mounted on a carriage 6, running on tracks 7, 8, and is driven by a spring barrel 9, and also has a rack 10 meshing with a pinion 11 connected to an escapement wheel 12, the escapement dogs being seen at 12^a. The rack 10 is hung on arms 13, so that it may be lifted from the pinion 11 to release the carriage.

Tabulator keys 14 are mounted upon levers 15, which, at their rear ends, raise the stop rods 16, having stops 17 at their upper ends. These stops may coöperate with interchangeably adjustable column stops 18, inserted, as required, in notches 19, 20, formed in the top and bottom of a bar 21, which is fixed to the carriage 6.

Each stop-rod has a shoulder 22 coöperating with a universal bar 23, which rocks about a pivot 24, and has an arm 25, which draws down a link 26 and vibrates a lever 27, the latter fulcrumed at 27^a and carrying a roll 27^b to run upon the under side of the rack bar 10, and lift the latter from the escapement pinion 11, whenever a key 14 is depressed.

The computing mechanism includes a drive shaft 28, having a bevel pinion 29 meshing with a pinion 30 upon a square shaft 31, the latter being splined to a master-wheel 32, which moves along the shaft and has spurs or teeth 33 to engage an internal set of teeth 34 formed upon a gang of computing wheels 35, the latter mounted in a casing 36 and also having exterior teeth to mesh with gears 38, the latter having number wheels 39. The master-wheel 32 is swiveled in a traveling hollow mandrel or arbor 40, within which the master-wheel shaft 31 may project, the swivel-joint being shown at 41, and permitting the master-wheel 32 to be rotated by the shaft 31, while said master-wheel is caused to travel in axial direction by the mandrel or arbor 40.

The drive shaft 28 may be driven and controlled either directly by the numeral keys 1 or in any other suitable manner, as for instance in the manner set forth in pending application No. 569,502; filed June 29, 1910. Since the driving means for said shaft form no part of the present invention, it is deemed unnecessary to illustrate the same. The shaft, it will be understood, is rotated automatically upon the depression of any of the numeral keys 1, the extent of rotation depending upon which key is depressed.

The mandrel 40 is moved endwise by means of a forwardly and rearwardly extending lever 42, pivoted midway of its ends

by means of gudgeons 43, so as to swing in a horizontal plane. At its forward end the lever is slotted at 44 to engage a pin 45 projecting from the carriage which carries the mandrel 40; said carriage comprising a tube 46 sliding upon a fixed rod 47, and also an arm 48, sliding upon a fixed horizontal rod 49; the mandrel 40 being secured to the forward end of the arm 48 by means of a set-screw 50. The movement of the mandrel 40 is of course only sufficient to enable the master-wheel 32 to travel the length of the gang of computing wheels 35, one of which is provided for each number wheel 39. The rod 47 coöperates with two similar rods or studs 49 and 47^b, all projecting from a framework plate or bracket 47^c, to carry a small plate 47^d which also supports the end of rod 49. It will be seen that 49 and 47^b, Fig. 5, carry the casing 36.

At its rear end, the lever 42 has a slot 51 to engage a pin 52 projecting down from a slide 53, the latter carrying the stem 54 of a hook 55, adapted to engage lugs 56 formed upon the blades or stops 18 which are forked to fit into the double rack 19, 20, for connecting the paper carriage 6 to the master-wheel 32 to cause the latter to travel step-by-step with the paper carriage.

The slide 53 works in a tubular guide or housing 58, which is slotted on its under side at 59 to permit the pin 52 to pass down to the lever 42. The stem 54 of the hook passes through a longitudinal perforation in the slide 53, and is adjustably secured to the latter by set screws 60. This permits slight longitudinal adjustment of the hook in order to enable the master-wheel 32 to be adjusted properly relatively to the computing wheels 35 while the hook is engaged by one of the lugs 56. The rack 21 has at 60^a the usual provision for longitudinal adjustment. The slide 53 has a feather 61, to fit into the slot 59, to prevent the slide and the hook from turning in the tube.

The hook has a notch 62 to enable it to engage any of the lugs 56. The hook normally springs up to engage the adjacent lug. For this purpose the hook may be made resilient or flexible, and a compression spring 63 may be employed to aid or cause the upward movement of the hook; said spring housed in a boss 64, and confined by a screw 65, and pressing a plunger 66 up against a straight portion of the under side of the hook, thus holding the latter up while permitting it to move freely endwise. The boss 64 is formed on a bushing 67, which is vertically slotted at 68 to form a guide for the hook; said bushing serving as a plug to close this end of the tubular housing 58.

When the hook is in engagement with one of said lugs 56, it is carried with the paper carriage 6 in letter-feeding direction to cause the lever 42 to swing upon its pivot and there-

by drive the mandrel 40 and the master-wheel 32 in the opposite direction. As the keys 1 are operated to write figures in the column, the master-wheel 32 is correspondingly rotated in any usual or suitable manner, to rotate the corresponding computing wheels 35. When the master-wheel has advanced past the computing wheel 35 of lowest denomination, a cam 69 formed on the hook 55 engages a projection 70 fixed upon the framework of the machine, and is thereby forced downwardly, to withdraw the hook 55 from that lug 56 with which it has been in engagement. As soon as the hook is released, a returning spring 71 connected to the lever 42 swings the latter in the opposite direction, carrying the master-wheel 32 backwardly, that is, toward the computing wheel 35 of highest denomination; this movement continuing until the hook 55 engages the succeeding lug 56, said hook being pressed up to engage said lug by means of the spring 63, and the lug becoming fully seated in the notch 62.

The writing of the numbers in the succeeding column will now proceed, and said number will be accumulated on said computing wheels by the number wheels 39, in the manner already referred to.

When returning the carriage 6 to begin a new line of writing, if the hook 55 is in engagement with one of the lugs 56, it is carried until a cam edge 72 thereon strikes a stud or roller 73, which may be pivoted upon a screw 74, threaded into the top of the boss 64; and by means of said roller or obstruction, the hook is cammed downwardly and released from the lug 56. The spring 63 immediately lifts the hook again, and the lugs 56 in succession ride freely over a bevel 40 or point 75 formed on the tip of the hook; the last lug in the series being caught and held by the hook when the carriage begins to run in letter-feeding direction.

In the present instance each of the tabulating keys 14 is a column-selecting key, and, when depressed, serves to bring the carriage 6 to a predetermined column. One manner of effecting this kind of tabulating consists in having the stop-rods 16 of assorted lengths, and having the column stops 18 of assorted depths, so that, the strokes of the stop-rod being uniform, each rod co-operates with its associated stop, regardless of the position of the latter along the rack. The first stop-rod 16 in the series (the rod at the extreme right at Fig. 4) is preferably the longest, to engage the first column stop 18. The next stop-rod 16 is too short to catch the first stop 18, but is long enough to catch the second stop 18; and so on.

The connection between the tabulating keys and the computing mechanism comprises a horizontal rock-shaft 80, extending across the machine beneath the tabulating key levers 15 and forward of the fulcrum

81 of the latter and suitably supported upon the framework. This rock-shaft 80 may be rocked by means of forward and rear universal bars 82, 83, fixed upon two pairs of arms 84, 85, extending forwardly and rearwardly from the ends of said rock shaft, the whole making a rocking frame.

Certain of the tabulating levers 15 have downwardly extending projections or toes 86 forward of the rock-shaft 80 and overlying the universal bar 82, so that when any one of said certain keys is depressed, the rocking frame is rocked to the position seen at Fig. 1. By means of an arm 87 fixed upon said rock-shaft, a link 88 is thus thrust up, said link being connected at its upper end with a lever 89 pivoted at 90 between its ends, and having means for reversing the direction of operation of the computing mechanism, so that subtraction will be performed.

It should be explained that in said Underwood machine, the pinion 29 and the counter-pinion 91 are loosely mounted upon the drive shaft 28, and both in mesh with the bevel pinion 30. Splined to said drive shaft 28 is a double clutch 92 having a connection at 93 to the lever 89. When said lever is vibrated by the upward thrust of the link 88 (or by a down push on the handle 94) the clutch 92 is carried down and engages with corresponding clutch teeth formed internally at 95 upon the pinion 29; but when the clutch is thrust up from the neutral position at Fig. 3, it connects similarly with the upper pinion 91, so that the machine is caused to add. The clutch 92 is splined to the shaft 28, as set forth in said application.

It should also be explained that the tens carrying operation in said Underwood machine is assisted by a constantly revolving friction shaft 96, upon which is fixed a bevel pinion 97, which is connected to a constantly rotating drive shaft 98 by means of pinions 99, 100, both in mesh with the pinion 97 and both loose on the shaft 98, and either of which may be connected with the shaft 98 by a clutch device 101, splined upon the shaft 98 and controlled by the lever 89, all as set forth in said application. The shaft 28 revolves intermittently at the operation of the numeral keys 1 of the typewriter, and the extent of the rotation depends upon the key selected.

Certain of the other tabulating key levers 15 are provided in rear of the rock shaft 80 with downwardly extending projections 102 to depress the universal bar 83 and turn the entire rocking universal bar or frame 125 to the position seen at Fig. 2, thus acting through the arm 87, link 88 and clutch lever 89 to restore the computing mechanism to position for performing addition.

One or more of the tabulating levers 15

may be provided at both front and rear of the rock-shaft 80 with short downwardly extending projections 103, so that when such lever is depressed, both universal bars 82, 83 will be engaged, and the universal rocking frame will be brought to central or neutral position, as at Fig. 3, and the clutch lever 89 will be brought to neutral position, so that when the typewriting machine is writing the column selected by such tabulator key, neither addition nor subtraction will be performed upon the computing mechanism, notwithstanding the operation of the driving shafts 28 and 98.

15 There may be provided upon the rock-shaft a yielding arm 104 having a pin or detent 105 to engage any of three holes 106 formed in the bracket 107 to hold the universal rocking frame in any of its three 20 positions. Any of the tabulating keys may move said rocking frame to its predetermined position from either of the other positions thereof.

The usual bichrome ribbon mechanism of 25 an Underwood typewriting machine comprises a universal bar 108 operated by heels 109 of the type bars and connected to the dogs 12^a which feed the paper carriage 6. Upon said universal bar is fixed a bracket 30 110 which carries a slotted actuator 111 to engage one of two wrists 112, 113 upon a lever 114, to which is pivoted an upstanding ribbon carrier 115 in front of the platen. The actuator 111 is usually two-armed, and 35 by shifting the same on the bracket 110, the actuator is moved alternately into and out of engagement with the wrists 112 and 113 on the lever 114. This shifting of the actuator 111 is usually effected by a link 116 40 pivoted at 117 to an arm 118 extending up from a horizontal rock-shaft 119 which extends forwardly and carries at its forward end a two-armed lever 120 having keys 121, 122, and also having a detent 123 to engage 45 a V-spring 124, whereby the lever is held in the position shown at Fig. 6, or in that shown at Figs. 8 and 9.

To this bichrome mechanism is connected a link 125, the latter having at its upper 50 end a slot 126 to engage a pin 127 upon the lever 120. The link is pivoted at its lower end at 128 to an arm 129 fixed upon the rock shaft 80.

When the parts are in the position seen at 55 Figs. 3, 7 and 9, the computing mechanism is neutral, and the ribbon mechanism is in position to expose the black stripe of the ribbon to the action of the types; the actuator or yoke 111 being connected to the upper wrist 112; but when any subtraction tabulator key is depressed, as at Fig. 1, the link 125 is thrust up to the Figs. 4 and 6 position, thus rocking the lever 120 and the rock-shaft 119, and vibrating the arm 118 65 through the link 116, shifting the actuator

111 so that the lower wrist 113 is connected to said actuator, and thus the lever 114 is vibrated at each stroke enough to carry up the red or special stripe of ribbon to be struck by the types. This shifting of the 70 ribbon and the lever 94 takes place of course before the carriage of the typewriter reaches the computing column. Of course, the detent 105 serves to hold the subtraction shifting mechanism in working positions so that 75 the operator may release the key 14 and permit the carriage 6 to become reconnected to its escapement devices, and may manipulate the keys for writing in the column on the work sheet.

It will be noted that the pin 127 and slot 126 coöperate in the following manner with the V-shaped spring 124, so as to set the lever 120 which controls the ribbon shift. If the mechanism be in adding position, as diagrammatically shown in Fig. 8, and then is shifted by the operation of a tabulating key to the Fig. 9 position, it will be seen that the slot 126 will permit the link 125 to rise almost idly with respect to the pin 127. 80 Whatever motion is communicated to the lever 120 by the link 125 will not be sufficient to carry the pin 123 on said lever 120 past the V-shaped spring 124, and thus the mechanism, which in adding writes black, 85 will in its neutral position also write black. If now the mechanism is shifted to subtraction, the link 125 will cause the lower end of the slot 126 to raise the pin 127 to such an extent that the lever 120 will force its 90 pin 123 past said spring 124, and then the resiliency of said spring will swing the parts to the position seen in Fig. 6, where the pin 127 stands well toward the top of said slot. If now the tabulating key be depressed, 95 which shifts the mechanism to neutral, the link 125 will draw the lever 120, so that its pin 123 will slip past the spring 124 and resiliency in the spring will throw the lever 120 back to the position shown in Fig. 9. 100 105

After depressing and releasing any tabulating key 14, the rocking frame 82, 83, etc., of course remains in the position to which it has been set by said key, and until another tabulating key is operated; but of 110 course the invention is not limited to a tabulating mechanism of this character and operation.

Variations may be resorted to within the scope of the invention, and portions of the 120 improvements may be used without others.

Having thus described my invention, I claim:

1. In a combined typewriting, tabulating and computing machine, comprising a typewriter carriage and a computing device including a device shiftable to different positions for determining whether the computing device shall add or subtract the amounts written by the typewriter, the combination 125 130

- with tabulating devices connected to the typewriter carriage, of means connecting said tabulating devices to said shiftable device, to determine whether the computing device shall add or subtract the numbers written in the several columns to which the typewriter carriage is brought by the tabulating mechanism.
2. In a combined typewriting, tabulating and computing machine, comprising a typewriter carriage and a computing device including a device shiftable to different positions for determining whether the computing device shall add or subtract the amounts written by the typewriter, said device also shiftable to make the computing device neutral or inoperable, the combination with tabulating devices connected to the typewriter carriage, of means connecting said tabulating devices to said shiftable device, to determine whether the computing device shall add or subtract the numbers written in the several columns to which the typewriter carriage is brought by the tabulating mechanism, or remain silenced during the writing of the numbers.
3. In a combined typewriting, tabulating and computing machine, comprising a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for subtraction.
4. In a combined typewriting, tabulating and computing machine, comprising a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for subtraction, and for enabling another of said keys to shift said shiftable device to position for addition.
5. In a combined typewriting, tabulating and computing machine, comprising a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for subtraction, and for causing the computing device to effect subtraction of the amounts written.
6. In a combined typewriting, tabulating and computing machine, comprising a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for subtraction, and for enabling another of said tabulating keys to shift said shiftable device to neutral position, so that no computation is done during the writing of numbers on the typewriter.
7. In a combined typewriting, tabulating and computing machine comprising a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for addition, and for enabling another of said tabulating keys to shift said shifting device to neutral position, so that no computation is done during the writing of numbers on the typewriter.
8. In a combined typewriting, tabulating and computing machine, comprising a typewriter carriage, column-selecting tabulator mechanism, and a computing device, the combination of a shiftable element for making the computing device effective for either adding or subtracting the amounts written, and means for connecting said column-selecting means to said shiftable element, to control the latter.
9. In a combined typewriting, tabulating and computing machine, comprising a typewriter carriage, column-selecting tabulator mechanism therefor, and a computing device, the combination with a set of independently operable column-selecting keys forming part of the tabulator mechanism, of an element movable by certain of said keys for causing the computing device to effect subtraction of the amounts written.
10. In a combined typewriting, tabulating and computing machine, comprising a type-

- 6 writer carriage, column-selecting tabulator mechanism therefor, and a computing device, the combination with a set of independently operable column-selecting keys 5 forming part of the tabulator mechanism, of an element movable by certain of said keys for causing the computing device to effect subtraction of the amounts written, and means for enabling another of said 10 column-selecting keys to cause the computing device to effect addition of the amounts written.
11. In a combined typewriting, tabulating and computing machine, comprising a typewriter carriage, column-selecting tabulator mechanism therefor, and a computing device, the combination with a set of independently operable column-selecting keys 15 forming part of the tabulator mechanism, of an element movable by certain of said keys for causing the computing device to effect subtraction of the amounts written, means for enabling another of said column-selecting keys to cause the computing device to effect addition of the amounts written, and means for enabling still another of said column-selecting keys to silence the computing device.
12. In a combined typewriting and computing machine, the combination with typewriting mechanism including a traveling carriage, of computing mechanism, tabulating mechanism for determining the various computing zones said carriage shall occupy, 20 mechanism for determining the state of said computing mechanism, and means to enable said zone-controlling means to control said state-determining mechanism to accord the character of the computation with the 25 zonal position of the carriage.
13. The combination of a typewriter carriage, a computing mechanism, a shiftable device for causing said computing mechanism to be effective for either addition or 30 subtraction, a tabulator mechanism for said carriage including a set of keys, a bar operable by any of a plurality of said keys, and a connection from said bar to said shiftable device.
14. The combination with a typewriter carriage and a computing mechanism, of a device shiftable to different positions for determining whether the computing mechanism shall add or subtract, a tabulating 35 mechanism for said carriage, said tabulating mechanism including a series of keys, a member movable in one direction by certain of said keys and in the opposite direction by other of said keys, and a connection 40 from said movable member to said shiftable device to control the operation of the computing mechanism.
15. The combination with a typewriter carriage and a computing mechanism, of a device shiftable to different positions for 45 determining whether the computing mechanism shall add or subtract, a tabulating mechanism including a series of keys, a universal bar or frame extending along said series of keys, certain of said keys constructed 50 to engage the forward portion, and certain of said keys constructed to engage the rear portion of said universal bar, to move the latter in opposite directions, and a connection from said universal bar to said shiftable device to control the operation of the computing mechanism.
16. The combination with a typewriter carriage and a computing mechanism, of a device shiftable to different positions for determining whether the computing mechanism shall add or subtract, a tabulating mechanism including a series of keys, a universal bar or frame extending along said series of keys, certain of said keys constructed 55 to engage the forward portion, and certain of said keys constructed to engage the rear portion of said universal bar, to move the latter in opposite directions, and a connection from said universal bar to said shiftable device to control the operation of the computing mechanism; another of said keys having means for bringing said universal bar or frame to middle position to silence 60 the computing mechanism.
17. In a combined typewriting and computing machine, the combination with a typewriter carriage and numeral printing keys, of computing mechanism under the control of said numeral printing keys, tabulating mechanism controlling the typewriter carriage and means operated by said tabulating mechanism for controlling the state of said computing mechanism and the characteristic of the printing by said numeral printing keys.
18. In a combined typewriting, tabulating and computing machine, comprising a shiftable ribbon mechanism and a typewriter carriage, and also comprising computing mechanism inclusive of a device shiftable to set the mechanism to perform either addition or subtraction when the amounts are written by the typewriter, the combination with tabulating devices connected to 115 the typewriter carriage, and including a set of independently operable keys, of means for enabling one of said tabulating keys to shift said shiftable device to position for subtraction and to shift said ribbon mechanism, and for enabling another of said keys to shift said shiftable device to position for addition and restore said ribbon mechanism to its first position.
19. In a combined typewriting, tabulating and computing machine, comprising a shiftable ribbon mechanism and a typewriter carriage, and also comprising computing mechanism inclusive of a device shiftable to set the mechanism to perform 120
- 65

either addition or subtraction when the amounts are written by the typewriter, the combination with tabulating devices connected to the typewriter carriage, and including a set of independently operable keys, of means for enabling one of said tabulating keys to shift said shiftable device to position for subtraction and to shift said ribbon mechanism, and for enabling another of said keys to shift said shiftable device to position for addition, and for enabling another of said tabulating keys to shift said shiftable device to neutral position, so that no computation is done during the writing of numbers on the typewriter; means being also provided for enabling each of the last mentioned keys to restore said ribbon mechanism to its original position.

20. In a combined typewriting, tabulating and computing machine, comprising a shiftable ribbon mechanism and a typewriter carriage, and also comprising computing mechanism inclusive of a device shiftable to set the mechanism to perform either addition or subtraction when the amounts are written by the typewriter, the combination with tabulating devices connected to the typewriter carriage, and including a set of independently operable keys, of means for enabling one of said tabulating keys to shift said shiftable device to position for subtraction and to shift said ribbon mechanism, and for enabling another of said tabulating keys to restore said ribbon mechanism and shift said shiftable device to neutral position, so that no computation is done during the writing of numbers on the typewriter.

21. In a combined typewriting, tabulating and computing machine, comprising a shiftable ribbon mechanism, a typewriter carriage, column-selecting tabulator mechanism therefor, and a computing device, the combination with a set of independently operable column-selecting keys forming part of the tabulator mechanism, of an element movable by certain of said keys for shifting said ribbon mechanism and causing the computing device to effect subtraction of the amounts written, and means for enabling another of said column-selecting keys to cause the computing device to effect addition of the amounts written and to restore the ribbon mechanism to its original condition.

22. In a combined typewriting, tabulating and computing machine, comprising a shiftable ribbon mechanism, a typewriter carriage, column-selecting tabulator mechanism therefor, and a computing device, the combination with a set of independently operable column-selecting keys forming part of the tabulator mechanism, of an element movable by certain of said keys for shifting said ribbon mechanism and causing the computing device to effect subtraction of the

amounts written, means for enabling another of said column-selecting keys to cause the computing device to effect addition of the amounts written, and means for enabling still another of said column-selecting keys to silence the computing device, means being provided for enabling either of the two last mentioned keys to restore said ribbon mechanism to its original position.

23. The combination of a typewriter carriage, a computing mechanism, a shiftable device for causing said computing mechanism to either add or subtract, a tabulator mechanism for said carriage including a set of keys, a bar operable by any of a plurality of said keys, a connection from said bar to said shiftable device, and a shiftable ribbon mechanism also connected to said bar.

24. The combination with a typewriter carriage and a computing mechanism, of a device shiftable to different positions for determining whether the computing mechanism shall add or subtract, a tabulating mechanism for said carriage, said tabulating mechanism including a series of keys, a member movable in one direction by certain of said keys and in the opposite direction by another of said keys, a connection from said movable member to said shiftable device to control the operation of the computing mechanism, and a shiftable ribbon mechanism also connected to said movable member.

25. The combination with a typewriter carriage and a computing mechanism, of a device shiftable to different positions for determining whether the computing mechanism shall add or subtract, a tabulating mechanism including a series of keys, a universal bar or frame extending along said series of keys, certain of said keys constructed to engage the forward portion, and certain of said keys constructed to engage the rear portion of said universal bar, to move the latter in opposite directions, a connection from said universal bar to said shiftable device to control the operation of the computing mechanism, and a shiftable ribbon mechanism also connected to said universal bar.

26. The combination with a typewriter carriage and a computing mechanism, of a device shiftable to different positions for determining whether the computing mechanism shall add or subtract; a tabulating mechanism including a series of keys; a universal bar or frame extending along said series of keys; certain of said keys constructed to engage the forward portion, and certain of said keys constructed to engage the rear portion of said universal bar, to move the latter in opposite directions; a connection from said universal bar to said shiftable device to control the operation of the computing mechanism; another of said keys

- having means for bringing said universal bar or frame to middle position to silence the computing mechanism, and a shiftable ribbon mechanism connected to said universal bar to be shifted thereby. 27. The combination with a tabulating mechanism including column-selecting keys, and a computing mechanism capable of performing either addition or subtraction, of shiftable means connected to the tabulating mechanism to determine whether the computing mechanism shall add or subtract, and a letter-feeding typewriter carriage controllable by said tabulating mechanism. 28. The combination with a tabulating mechanism including column-selecting keys, and a computing mechanism capable of performing either addition or subtraction, of shiftable means connected to the tabulating mechanism to determine whether the computing mechanism shall add or subtract or remain neutral at the typewriting operation, and a letter-feeding typewriter carriage controllable by said tabulating mechanism. 29. The combination with a typewriting mechanism, a computing mechanism, and a tabulating mechanism including tabulating keys, of means shiftable to different positions by different tabulator keys, for setting said computing mechanism to perform either addition or subtraction, or to remain neutral at the subtraction operation, and a multi-color ribbon mechanism simultaneously shiftable by said tabulating mechanism. 30. In a computing machine, the combination with a series of tabulating key levers, of extensions on said levers, a universal bar, an extension on said universal bar to operate with one of said extensions to move said universal bar in one direction, another extension on said universal bar to coöperate with another extension on a lever, computing wheels, means for turning said computing wheels, and a connection from said universal bar for determining when and how said computing wheels shall be turned. 31. In a combined typewriting and computing machine, the combination with a traveling carriage and computing wheels, of tabulating keys for positioning said traveling carriage, means for turning said computing wheels, and means positively positioned by the operation of a tabulating key for determining how said computing wheels shall be operated. 32. In a combined typewriting and computing machine, the combination with a traveling carriage and computing mechanism, of tabulating keys for positioning said carriage, settable stops on said carriage for so positioning it, extensions on said stops to determine at what point or zone in the travel of the carriage the computing mechanism shall operate, and means to enable said keys to determine how said computing mechanism shall operate when in the particular zone determined by any one of said stops. 33. In a combined typewriting and computing machine, the combination with computing wheels and a clutch for said wheels, of a lever by which said clutch is controlled, a handle for said lever, a link depending from said lever, and a universal bar to which said link is pivoted. 34. In a combined typewriting and computing machine, the combination with numeral keys and computing wheels, of a clutch for determining how said keys shall affect said wheels, a lever on which the seizing member of said clutch is pivoted, a handle for swinging said lever, a link depending from the opposite end of said lever, a rock arm operated by said link, and a detent fast to said rock arm for holding said lever positioned. 35. In a combined typewriting and computing machine, the combination with a computing mechanism, of an array of column-selecting keys, a rock shaft operable by said keys, and means operable by said shaft for determining whether said computing mechanism shall add or subtract. 36. In a combined typewriting and computing machine, the combination with numeral keys, a computing device, and a traveling carriage, of means for positioning said carriage, means connected to said positioning means for setting said computing device to compute in a given manner, and a handle settable after said positioning means has been made effective to positively determine whether said computing device shall add, subtract or be neutral. 37. In a combined typewriting and computing machine, the combination with numeral keys, a computing device, and a traveling carriage, of printing mechanism adapted to print in more than one color, means for positioning said carriage and simultaneously determining how said printing means shall print, and a handle adapted to positively determine independently of said positioning means how the printing means shall print for that column. 38. In a combined typewriting and computing machine, the combination with numeral keys, of a totalizer and a traveling carriage controlled by said keys, printing mechanism adapted to print in more than one color, stops settable along said carriage, and manipulatable devices to coöperate with said stops, said stops and manipulatable devices acting to position said carriage in different columns, to determine the characteristic of the printing for the column selected, and to determine in what column the totalizer shall be effective. 39. In a combined typewriting and com-

- puting machine, the combination with numeral keys and a traveling carriage, of means for positioning said carriage, a computing device, a lever adapted to determine whether said computing device shall add or subtract, a connection between said positioning means and said lever whereby the positioning means positively places said lever in one of its effective positions, means for holding said lever wherever set until moved by a subsequent operation of said carriage-positioning device, and a handle for independently setting said lever at any desired position of adding or subtracting.
40. In a combined typewriting and computing machine, the combination with numeral keys and a traveling carriage, of means for positioning said carriage, a computing device, a lever adapted to determine whether said computing device shall add, subtract or be neutral, a connection between said positioning means and said lever whereby the positioning means positively places said lever in one of its effective positions, means for holding said lever wherever set until moved by a subsequent operation of said carriage-positioning device, and a handle for independently setting said lever at any desired position of adding, subtracting or neutral.
41. In a combined typewriting and computing machine, the combination with numeral keys and a traveling carriage, of a totalizer, column-selecting stops for determining in what columns said totalizer shall be effective, coöperating column-selecting keys adapted to determine whether said totalizer shall add or subtract when the carriage is at any particular column, and a series of counter-stops each connected to its own column key and having a different point of effectiveness from every other counter-stop to selectively arrest said carriage at its own column and no other.
42. In a combined typewriting and computing machine, the combination with numeral keys and a computing device, of a traveling carriage, an array of column-selecting keys adapted to position said carriage, a universal rock shaft adjacent said column-selecting keys and underlying them, a lever adapted to determine whether said computing device shall add or subtract and a link positively connecting said rock shaft to said lever.
43. In a computing machine, the combination with a computing device, of a series of levers for determining whether it shall add, subtract or be neutral, a rock shaft universal to said levers, a lug on one lever for determining by said shaft that the computing device shall add, a lug on another lever for determining by said shaft that the computing device shall subtract, and two lugs on another lever for positively determining by said shaft that said computing device shall neither add nor subtract.
44. In a computing machine, the combination with a computing device, of a series of levers for determining whether said computing device shall add, subtract or be neutral, a traveling carriage forming part of said computing device, column stops for arresting said carriage, and counter stops adapted to selectively coöperate with said column stops and connected to be selectively operated by said levers, whereby different positions of said computing device are determined and whereby its state is determined for any position.
45. The combination with a traveling carriage and a tabulating mechanism therefor, of a computing mechanism capable of performing either addition or subtraction, and means operated by said tabulating mechanism for determining whether said computing mechanism shall be effective to add or subtract before said carriage is completely positioned.
46. The combination with typewriting mechanism, a tabulating mechanism, and a computing mechanism capable of performing either addition or subtraction, of a typewriter carriage adapted to be positioned by said tabulating mechanism, means for positioning said carriage, and means operated by said positioning means to determine whether said computing mechanism shall be effective to add or subtract, said means being effective before the typewriter carriage is positioned.
47. In a combined typewriting and computing machine, the combination with a series of column-selecting keys, and column-stops, of counter-stops having extensions for variably coöperating with said column-stops, and means connected to said column-selecting keys for determining whether the mechanism shall add or subtract in any column determined by said column-stops and counter-stops.
48. In a combined typewriting and computing machine, the combination with a traveling carriage and computing mechanism, of tabulating key levers for positioning said carriage, settable stops on said carriage for so positioning it, means connected to said stops to determine at what point in the travel of the carriage the computing mechanism shall operate, extensions on said levers, and means to coöperate with said extensions for determining how said computing mechanism shall operate at the different points in the travel of the carriage as determined by said stops and the means connected thereto.
49. The combination with a combined typewriting and computing mechanism including a letter-feeding carriage, and capable of typewriting and computing in a

plurality of zones, of tabulating means for selectively jumping said carriage from the start to any desired zone and giving a predetermined state for that zone.

5 50. The combination with a registering mechanism, of actuating mechanism for said registering mechanism, a letter-feeding carriage, a tabulating mechanism for said carriage, and means controlled by said tabulating mechanism for determining the character of computing activity of said actuating mechanism.

51. The combination with a combined typewriting and computing machine capable of writing and computing in a plurality of zones, of a common means for selecting from the start any of said zones and determining the color of printing of the selected zone.

52. The combination with a computing head capable of being in a plurality of states as to adding, subtracting and remaining neutral, a carriage, and automatic means for concomitantly causing the movement of said carriage and means operated by said automatic means for changing the state of said computing head.

53. The combination with a computing head capable of existing under a plurality of states, of a carriage, and a key for concomitantly causing a movement of said carriage and means operated by said key for changing the state of said computing head.

54. The combination with a computing head having a series of computing wheels and a master wheel, said computing wheels and said master wheel having a movement relative to each other whereby said master wheel may cooperate successively with each of said computing wheels, of means for rotating said master wheel, and means controlled from a single point effective at any relative adjustment of said master wheel and said computing wheels for concomitantly reversing the direction of rotation of said master wheel and changing the relative position of said computing wheels and said master wheel.

55. The combination with a computing head capable of existing under a plurality of states as to adding, subtracting and remaining neutral, of a traveling carriage, means distinct and independent of said carriage for changing the state of said computing head, and means for concomitantly causing a traveling movement of said carriage and an actuation of said distinct means so as to effect a concomitant travel of said carriage and change in state of said computing head.

56. In a combined typewriting and computing machine, a carriage, a tabulating mechanism movable to control the jumping movements of the carriage, a computing mechanism convertible to different states, and means dependent upon movement of

said tabulating mechanism to convert the computing mechanism.

57. In a machine of the class described, the combination of numeral keys, a mechanism convertible to cooperate in different ways with said keys, and a typewriting mechanism including a traveling carriage; means for bringing said convertible mechanism into use in a plurality of zones during the traverse of the carriage, a tabulating device comprising keys for positioning said carriage in each of said zones, means controlled by any of said tabulating keys to determine for any zone the state of conversion or restoration of said convertible mechanism in the different zones.

58. A combined typewriting and computing machine having a carriage, type-operating numeral keys, tabulating mechanism for the carriage, computing mechanism capable of cooperation with said keys and convertible from a state to perform addition to either a state to perform subtraction or a neutral state, and means for determining the characteristic of the printing effected by said numeral keys, said characteristic-determining means convertible from one to another of two conditions, and connected with the convertible computing mechanism to operate under one condition for one state of said computing mechanism, and under the other condition for either of the remaining two states thereof.

59. In a combined typewriting and computing machine, a carriage, a tabulating device therefor, a mechanism to perform more than one kind of computation, and means controlling said mechanism, said controlling means dependent upon the movement of the tabulating device.

60. The combination with a carriage and tabulating mechanism therefor, of computing mechanism capable of performing either addition or subtraction, and means dependent upon the movement of said tabulating mechanism for determining whether said computing mechanism shall add or subtract.

61. The combination with a carriage and tabulating mechanism therefor, of computing mechanism including means for determining whether the computing mechanism shall add, subtract or be neutral, and means connected to said tabulating mechanism for operation therewith, for controlling the operation of said determining means.

62. The combination with a carriage and computing mechanism capable of performing either addition or subtraction, of means normally inoperative during the run of said carriage, for determining whether the computing mechanism shall add or subtract, and a tabulating mechanism operatively connected with means for actuating said determining means.

63. A combined typewriting and computing machine having a carriage, tabulating mechanism for the carriage including keys, and computing mechanism adapted to add or subtract; and comprising, in combination, 5 a drive for said computing mechanism, to determine whether it shall add or subtract, and means dependent upon the movement of the tabulator keys for determining whether 10 the computing mechanism shall add or subtract, said means acting through the medium of said drive.

64. The combination with a carriage and tabulating mechanism therefor, including a 15 set of keys, of computing mechanism capable of performing either addition or subtraction, and means including controlling devices dependent upon the movements of said keys, for determining whether said 20 computing mechanism shall add or subtract.

65. In a combined typewriting and computing machine, the combination with printing mechanism, a traveling carriage and

computing mechanism, of manually settable means for controlling the position of the 25 carriage for various columns, and means brought into action under control of said manual settable means for determining for each column the character of the computation and the characteristic of the printing in 30 said several columns.

66. In a machine of the class described, the combination of numeral keys, two mechanisms convertible to coöperate in different ways with said keys, a carriage, tabulating mechanism therefor, including keys; a shaft 35 controlling the conversion of one of said convertible mechanisms, a handle capable of controlling the other convertible mechanism, a link between said shaft and said handle, 40 and means to enable said tabulator keys to control said shaft.
